DOMESTIC WRINGING MACHINES

Carlton Clegg, Rochdale, England

Application November 9, 1953, Serial No. 391,001

3 Claims. (Cl. 68—263)

This invention relates to improvements in domestic wringers and other wringers or squeezers for attachment to electric or other washing machines.

The object of the invention is the provision of trip levers to release the pressure when desired.

According to the invention a cover plate is pivoted in or on end caps adapted when closing to rotate a pin on the pivot of the cover to engage heads of spring loaded bolts to apply pressure to the rollers and to engage catches on a trip lever mounted on the pivots of the end caps, release of the trip lever allowing the cover to pivot to relieve pressure.

The invention will be described with reference to the accompanying drawings:

Fig. 1 is a vertical section on line 1—1 Fig. 2 of a wringer according to the present invention,

Fig. 2 is a vertical section of the wringer on line 2—2 Fig. 1,

Fig. 3 is an end view of the trip lever mechanism with the wringer in the operative position.

Fig. 4 is a sectional plan on line 4—4 Fig. 2 showing the trip lever linkage in outside,

Fig. 5 is a section on line 5—5 Fig. 1 showing the trip lever mechanism in the released position.

Fig. 6 is a view similar to Fig. 5 showing the end caps pivoted to separate the rollers.

The wringer is formed with a frame A supporting a lower or bottom driven roller A¹ and an upper or top roller A² mounted to rotate in end caps B. The end caps B are pivoted at one end on axle pins b to the heads of bolts B¹ extending through the wringer frame A and provided with coil springs B² on their shanks arranged between a nut thereon and the frame A. The opposite ends of the end caps B are connected to the heads B³ of further similarly mounted springs B⁴ on bolts B⁵.

The heads of the bolts B³ are formed with recesses b¹ to receive pins b² passing through axle pins b³ passing through the end caps B, the pressure between the rollers A¹ and A² being released when the end caps are pivoted into the position shown in Figs. 5 or 6 and applied when the end caps are in the position shown in Figs. 2.

A cover plate C for the rollers carries the axle pins b³; when the cover plate is raised as shown in Fig. 5 the pins b² have turned and the cap is released from the heads B³ of the bolts B⁵ and the pressure between the rollers is relieved and the end caps B and top roller A² may be pivoted into the position shown in Fig. 6 clear of the bottom roller A¹.

The cover plate C is formed with pins c projecting from each end and engaging catch lugs d on bellcrank levers D (one at each end of the wringer), whereby the end caps B are retained in the operative position with the rollers A¹ and A² in pressure contact by the pins b² when the cover C is lowered.

Each bellcrank lever D is pivoted on an axle pin b and is formed with an arm d¹ and a second arm d² on which the catch lug d is formed. The arms d¹ at each end of the wringer are connected by a trip rod D¹ and the arms

d² extend transversely of the wringer. When the trip rod D¹ is moved vertically from the position shown in Figs. 1 and 2 the catch lugs d are moved away from the pins c on the cover thereby releasing the cover which moves into the position shown in Fig. 5 thereby releasing the end caps B from the heads B³ of the bolts B⁵ thereby removing pressure from the rollers and allowing the end caps to be pivoted into the position shown in Fig. 6.

In order to release the pressure from the rollers at both sides of the wringer a second trip rod D² is mounted on one arm d³ of bellcrank levers D⁰ pivoted on the axle pins b³, second arms d⁴ of which extend above the free ends of the arms d² whereby on an upward movement of the trip rod D² the arms d² are depressed to release the cover C.

The release of the pins c from the lugs d allows the cover C to move into the position shown in Fig. 5 thereby releasing the pin b² under the pull of the springs B⁴ from the heads B³ of the bolts B⁵ and relieving the pressure between the rollers A¹ and A². In order to limit the movement of the cover C and prevent it from flying back a slotted link d⁵ is mounted on the axle pin b³ outside of each of the end caps B, the slot in each of the links d⁵ being engaged by a pin d⁶ carried by a link d⁷, these pins connecting the links d⁵ respectively to the links d⁷. The links d⁷ are mounted on the axle pins b and limit the movement of the cover C to substantially 45°.

I claim:

1. A wringer comprising a frame, a lower roller mounted in the frame, end caps, pivots for the end caps, an upper roller journaled between the frame and end caps, a pair of spring loaded bolts passing through the frame on which the end caps are pivoted, a second pair of spring loaded bolts passing through the frame for retaining the end caps with the upper roller in pressure contact with the lower roller, axle pins journaled in the end caps, second pins passing through the axle pins and engaging in recesses in the second pair of spring loaded bolts, a cover plate which carries the axle pins, third pins on the cover plate, a pair of bell crank levers mounted on the pivots for the end caps, catch lugs on the bell crank levers engageable by the third pins on the cover plate to lock the end caps in their pressure position, a trip rod extending between said bell crank levers adapted on operation to rock the bell crank levers to release the cover plate and cause relief of the pressure from the rollers, a second pair of bell crank levers pivoted on the axle pins journaled in the end caps, arms on the first pair of bell crank levers, arms on the second pair of bell crank levers engageable with the arms on the first pair of bell crank levers, and a second trip rod extending between the second pair of bell crank levers adapted on operation to rock both pairs of bell crank levers to release the rollers.

2. A wringer comprising a frame, a lower roller mounted in the frame, end caps, pivots for the end caps, an upper roller journaled between the frame and end caps, a pair of spring loaded bolts passing through the frame on which the end caps are pivoted, a second pair of spring loaded bolts passing through the frame for retaining the end caps with the upper roller in pressure contact with the lower roller, axle pins journaled in the end caps, second pins passing through the axle pins and engaging in recesses in the second pair of spring loaded bolts, a cover plate which carries the axle pins, third pins on the cover plate, a pair of bell crank levers mounted on the pivots for the end caps, catch lugs on the bell crank levers engageable by the third pins on the cover plate to lock the end caps in their pressure position, a trip rod extending between said bell crank levers adapted on operation to rock the bell crank levers to release the cover plate and cause relief of the pressure from the rollers, a second pair of bell crank levers pivoted on the axle pins journaled in the end caps, second pins passing through the axle pins and engaging in recesses in the second pair of spring loaded bolts, a cover plate which carries the axle pins, third pins on the cover plate, a pair of bell crank levers mounted on the pivots for the end caps, catch lugs on the bell crank levers engageable by the third pins on the cover plate to lock the end caps in their pressure position, a trip rod extending between said bell crank levers adapted on operation to rock the bell crank levers to release the cover plate and cause relief of the pressure from the rollers, a second pair of bell crank levers pivoted on the axle pins journaled in the end caps, second pins passing through the axle pins and engaging in recesses in the second pair of spring loaded bolts.

axle pins journaled in the end caps, arms on the first pair of bell crank levers, arms on the second pair of bell-crank levers, engageable with the arms on the first pair of bell crank levers, a second trip rod extending between the second pair of bell crank levers and adapted on operation to rock both pairs of bell crank levers to release the rollers, a pair of slotted links pivoted on the pivots for the end caps, and further links pivoted on the axle pins carried by the cover plate and engaging the slotted links to limit the movement to the cover plate relatively to the end caps.

3. A wringer comprising a frame, a lower roller mounted in the frame, end caps, pivots for the end caps, an upper roller journaled between the frame and end caps, a pair of spring loaded bolts passing through the frame on which the end caps are pivoted, a second pair of spring loaded bolts passing through the frame for retaining the end caps with the upper roller in pressure contact with the lower roller, axle pins journaled in the end caps, second pins passing through the axle pins and engaging in recesses in the second pair of spring loaded bolts, a cover plate which carries the axle pins, third pins on the cover plate, a pair of bell crank levers mounted on the pivots for the end caps, catch lugs on the bell crank levers engageable by the third pins on the cover plate to lock the end caps in their pressure position, a trip rod extending

between said bell crank levers adapted on operation to rock the bell crank levers to release the cover plate and cause relief of the pressure from the rollers, a second pair of bell crank levers pivoted on the axle pins journaled in the end caps, arms on the first pair of bell crank levers, arms on the second pair of bell crank levers engageable with the arms on the first pair of bell crank levers, a second trip rod extending between the second pair of bell crank levers adapted on operation to rock both pairs of bell crank levers to release the rollers, a pair of slotted links pivoted on the pivots for the end caps, further links pivoted on the axle pins for the cover plate, and fourth pins on the further links passing through the slots in the slotted links to limit the movement of the cover plate relatively to the end caps.

between said bell crank levers adapted on operation to rock the bell crank levers to release the cover plate and cause relief of the pressure from the rollers, a second pair of bell crank levers pivoted on the axle pins journaled in the end caps, arms on the first pair of bell crank levers, arms on the second pair of bell crank levers engageable with the arms on the first pair of bell crank levers, a second trip rod extending between the second pair of bell crank levers adapted on operation to rock both pairs of bell crank levers to release the rollers, a pair of slotted links pivoted on the pivots for the end caps, further links pivoted on the axle pins for the cover plate, and fourth pins on the further links passing through the slots in the slotted links to limit the movement of the cover plate relatively to the end caps.
